CLAIM

The ornamental design for a remote customer banking kiosk, substantially as shown and described.

DESCRIPTION

FIG. 1 is a front perspective view of a remote customer banking kiosk showing my new design;

FIG. 2 is a front elevation thereof;

FIG. 3 is a side elevation thereof;

FIG. 4 is a rear elevation thereof;

FIG. 5 is a top plan view thereof; and

FIG. 6 is a bottom plan view thereof.
